UNITED STATES PATENT OFFICE.

WILLIAM W. MASSEY, OF ELYRIA, OHIO.

FOLDING AND EXTENSION MEASURING-ROD.

SPECIFICATION forming part of Letters Patent No. 230,640, dated August 3, 1880.

Application filed May 22, 1880. (No model.)

To all whom it may concern:

Be it known that I, WILLIAM W. MASSEY, a citizen of the United States, residing at Elyria, in the county of Lorain and State of Ohio, 5 have invented a new and useful Improvement in Folding and Extension Rods for Measuring and other Purposes, of which the following is a specification.

My invention relates to that class of measuring poles or rods which may be so folded as to admit it into a mechanic's ordinary tool-chest, or be so unfolded and extended that it may be readily converted into a straight measuring-rod of any desired length, or be so adjusted that it will form a large square or bevel of any desired angle, at the will of the operator. I attain these objects by the mechanism illustrated in the accompanying drawings, in which—

20 Figure 1 is a side elevation of one of the hinges. Figs. 2, 3 are end elevations of the respective arms of the hinge. Figs. 4, 5 are plan views of the same. Fig. 6 is a plan view of the hinge. Fig. 7 is a side elevation of a 25 detached arm of the hinge. Fig. 8 is a side elevation of the bolt used for locking the hinge. Fig. 9 is a perspective view of the rod when extended to its greatest length, having the extended portion broken off. Fig. 10 is a perspective view of the clamps and guides. Fig. 30 11 is an elevation of the rule when so adjusted as to form a square or bevel.

Similar letters refer to similar parts throughout the several views.

35 The bars A A' B B' constitute the rod. These bars are hinged together, as seen at C C'—that is, bars A A' are hinged together and form one distinct section of the rod, and bars B B' also in like manner form a similar section of 40 the rod. These sections are clasped together, as will more fully appear, so that they may freely slide almost their entire length.

D represents a clamp, which is seen in perspective in Fig. 10. Said clamp is secured to 45 the bars A' and B' at or near their ends by letting the tongue a into a gain cut across the inner surface of the bar. Said gain is cut somewhat deeper than the thickness of the tongue a, so that the tongue may be withdrawn 50 into the gain by means of the thumb-nut b on shank c, for the purpose of pressing the sec-

tions of the rod into close contact to prevent their slipping when the rod is set at any desired length.

d represents a tongue which is formed on 55 the tongue a. Said tongue d fits into groove e of the opposite section alternately. Said tongue d and groove e in the opposite section serve to guide and stiffen the rod when extended, while the clamp serves to hold the sections 60 in close contact, and at the same time allow them to slide freely, as well as to clamp the sections firmly together when desired.

The hinges C C are so constructed that when the sections of the rod are opened a sliding 65 bolt, f, is forced forward by means of a spiral spring, g, (shown in dotted lines, Fig. 1,) so as to effectually lock the joint and render it rigid until the bolt is again withdrawn. Said bolt f (see Fig. 8) is plain and straight, except 70 at its inner end, where it is chamfered, so as to form an inclined plane, q. This bolt may be square or round, as is most convenient.

When the joint is opened so that the rod becomes straight the spiral spring actuates the 75 bolt and forces it forward into a recess, h, in the center disk of the joint. The upper portion of said recess h consists of an inclined plane, (see Fig. 7,) under which the inclined plane of bolt f is forced, so that when these 80 two inclined surfaces impinge firmly all slack motion is taken up, and thus the rod is held rigidly in a straight position. When the bolt is withdrawn and the joint is slightly bent the bolt is held back by the periphery of the said 85 disk, against which it always presses.

The operation of my invention is as follows: The two sections are placed parallel to each other, both of them being opened out straight, so that the grooved sides come together, the 90 ends being even and the joints come opposite to each other, the ends i i' and the ends j j' each coinciding and forming the two ends of the united sections. The thumb-nut is then tightened and the joints are unlocked, and the 95 rod may be folded in a small compass.

When to be used as a measure the sections are opened and the joints are simultaneously locked. The thumb-nut is relieved, so that the sections of the rod will slide freely. They are 100 then drawn out to the desired length and are again firmly secured, thus forming an adjust-

able measure, which is of great advantage in taking distances in many places where a single rigid rod would be impracticable. When desired this rod can be converted into a serviceable and reliable large square by extending it to an indicated length, which may be marked on that portion of the sections which are contiguous to each other, as seen in Fig. 11, and the joints unlocked and the bars which form the outer ends of the sections brought to the position seen in said figure, where they are secured together by inserting a pin, *k*, through suitable holes, which are there provided for that purpose. In like manner any desired bevel may be made by loosening the thumb-nut and moving the bars such a distance as will give the required angle.

The pitch of a roof can be instantly obtained by sliding the sections to a given indicated point which will form the exact bevel for the rafters.

These instruments may be made of any desired length, and in view of the many and important practical purposes to which it is readily and reliably applied there can be no doubt 25 of its great utility.

What I claim as new, and desire to secure by Letters Patent, is—

1. The bolt *f*, having an inclined surface, *q*, and spiral spring *g*, in combination with recess 30 *h*, having its upper surface inclined, as described, for the purpose of rigidly locking the joint and taking up any slack motion, as described.

2. The clamp *D* and tongues *d*, in combination with grooves *e*, the same being constructed in the manner and for the purpose specified. 35

WM. W. MASSEY.
